UNITED STATES PATENT OFFICE

CHARLES APELT, OF COMFORT, TEXAS

DESIGN FOR A BED LAMP

Application filed March 25, 1930. Serial No. 35,021. Term of patent 7 years.

To all whom it may concern:

Be it known that I, CHARLES APELT, a citizen of the United States, residing at Comfort, in the county of Kendall and State of Texas, have invented a new, original, and ornamental Design for Bed Lamp, of which the following is a specification, reference being had to the accompanying drawing, forming part thereof.

I claim:

The ornamental design for a bed lamp, as shown.

CHARLES APELT.
